UNITED STATES PATENT OFFICE

161,296

COMBINED WATCHCASE AND BRACELET

Henry K. Tourneau, New York, N. Y.

Application April 19, 1950, Serial No. 9,313

Term of patent 14 years

(Cl. D45—4)

To all whom it may concern:

Be it known that I, Henry K. Tourneau, a citizen of the United States, residing in New York city, county and State of New York, have invented a new, original, and ornamental Design for a Combined Watch Case and Bracelet, of which the following is a specification, reference being had to the accompanying drawing, forming a part thereof, in which:

Fig. 1 is a top plan view of a combined watch case and bracelet, showing my new design;

Fig. 2 is a side elevational view thereof, and
Fig. 3 is an end elevational view thereof.

I claim:

The ornamental design for a combined watch case and bracelet, as shown.

HENRY K. TOURNEAU.
